(57) **CLAIM**

We claim the ornamental design for a tree engaging cleat, as shown.

DESCRIPTION

FIG. 1 is a front perspective view of a tree engaging cleat; FIG. 2 is a rear perspective view of the tree engaging cleat of FIG. 1;

FIG. 3 is a top view of the tree engaging cleat of FIG. 1; FIG. 4 is a front perspective view of the tree engaging cleat of FIG. 1;

FIG. 5 is a rear perspective view of the tree engaging cleat of FIG. 4;

FIG. 6 is a front view of the tree engaging cleat of FIG. 4; FIG. 7 is a rear view of the tree engaging cleat of FIG. 4; FIG. 8 is a top view of the tree engaging cleat of FIG. 4; FIG. 9 is a bottom view of the tree engaging cleat of FIG. 4;

FIG. 10 is a first side view of the tree engaging cleat of FIG. 4; and,

FIG. 11 is a second side view of the tree engaging cleat of FIG. 4.

The broken lines are for the purpose of illustrating environment (e.g., a tree climbing stick, a tree stand frame, and so on) and form no part of the claimed design.
